UNITED STATES PATENT OFFICE.

ALBERT J. GURNEY, OF CANTON, OHIO, ASSIGNOR TO THE AMERICAN MINE DOOR CO.,
OF CANTON, OHIO, A CORPORATION OF OHIO.

WIRE ANCHOR.

Application filed July 17, 1925. Serial No. 44,348.

This invention relates to an improved wire anchor particularly designed for use in anchoring signal wires as disclosed in Patent No. 1,523,805 for a signaling system for mines granted to me January 20, 1925, or in anchoring feeder wires of the overhead trolley wire systems of mines.

The invention seeks, among other objects, to provide an anchor which may be conveniently employed in a limited space and which will be adapted to anchor a signal wire or feeder wire in a position directly over a trolley wire and close thereto.

The invention seeks, as a further object, to provide an anchor which may be readily adjusted for stretching the wire engaged thereby and anchoring the wire taut.

And the invention seeks, as a still further object, to provide an anchor embodying a novel wire engaging clamp, and wherein the clamp will be formed to securely grip the wire.

Other objects of the invention not above specifically mentioned will appear as the description proceeds.

In the accompanying drawings:

Figure 1 is a plan view showing my improved anchor in connection with a trolley wire, signal wire, and feeder cable and also illustrating hangers for said wires and the cable.

Figure 2 is a side elevation better showing the disposition of the anchor with respect to the trolley wire, signal wire and cable.

Figure 3 is a longitudinal sectional view through the anchor clamp on the line 3—3 of Figure 1, looking in the direction of the arrows.

Figure 4 is a front end elevation of the anchor clamp.

Figure 5 is a detail view of the movable jaw of the clamp.

Referring now more particularly to the drawings, I have shown the present anchor in connection with a trolley wire 10, signal wire 11, and feeder cable 12. I have also illustrated a hanger 13 as disclosed in my co-pending application filed January 13, 1925, Serial No. 2226, as well as a second hanger 14 as disclosed in my co-pending application filed January 13, 1925, Serial No. 2227. It is, therefore, unnecessary, in the present instance, to describe said hangers in detail. However, it may be observed that the hanger 13 is constructed to insulatingly

support the signal wire 11 directly over the trolley wire 10 and is also constructed to support the cable 12 directly over the signal wire, the cable being electrically connected with the trolley wire through the hanger. 60 The hanger 14 is a single wire hanger and is constructed to support the trolley wire alone. Both of said hangers are carried by insulators 15 and my purpose in showing said hangers is to bring out the fact that the improved anchor is peculiarly adapted for use in a system employing said hangers in conjunction with one or more wires, as illustrated.

In accordance with the present invention, 70 I employ a wire engaging clamp which includes a substantially rectangular body member having parallel side bars 16 integrally connected by forward and rear cross bars 17 extending between the upper sides 75 of the side bars. The forward cross bar is reinforced by upstanding reinforcing ribs 18 extending from end to end of said bar in spaced relation while the rear cross bar is reinforced by a single upstanding longitudinal reinforcing rib 19 which is, however, much more pronounced than the ribs 18 and projects considerably thereabove. Integrally formed on the rear cross bar at its ends are rearwardly elongated eyes 20 and similarly formed on the cross bars midway between the side bars is a longitudinally disposed fixed jaw 21 inclined from its rear end downwardly toward its forward end. Preferably, said jaw is provided with a concave 90 lower face, and, as brought out in Figure 3, the rear end of said jaw lies above the lower faces of the side bars 16 while the forward end of said jaw lies below said faces.

Integrally formed on the side bars 16 of 95 the body member near the rear ends of said bars are companion inwardly directed flanges 22, and slidably supported by said flanges is a channel-shaped movable jaw 23 straddling the fixed jaw 21 to coact therewith. The jaw 23 is substantially U-shaped in cross section and integrally formed on the side portions of said jaw are side flanges 24 slidably coacting with the flanges 22. Formed at the bottom of the movable jaw 100 are spaced transverse gripping ribs 25 and, as shown in Figure 5, said jaw is gradually tapered in depth to conform to the inclination of the fixed jaw so that the bottom of the movable jaw is always disposed parallel 105 110

to the fixed jaw. However, as the movable jaw is advanced or shifted forwardly upon the body member, the bottom of the movable jaw will, due to the inclination of the fixed jaw with respect to the flanges 22, be caused to gradually approach the fixed jaw. The movable jaw is detachable and may be removed at the rear end of the body member.

In conjunction with the clamp, I employ a pair of turnbuckles 26 which are provided at their forward ends with hooks 27 to engage the eyes 20 of the body member of the clamp while at their rear ends, said turnbuckles are provided with eyes 28 to engage anchoring studs 29. To install the device, the studs 29 are arranged to project from the wall or roof of the mine at opposite sides of the plane of the trolley wire 10, when the eyes 28 of the turnbuckles are engaged with said studs. The eyes 20 of the body member of the clamp are then engaged with the hooks 27 of said turnbuckles, when the fixed jaw 21 of said member is positioned against the cable 12 at its upper side. The movable jaw 23 is then arranged to embrace the cable and is engaged with the flanges 22 of the body member, when said jaw is manually advanced to grip the cable between the jaws. Accordingly, by then adjusting the turnbuckles 26, the cable may be drawn taut and, as will be seen, pull upon the cable will cause the movable jaw to be further advanced upon the body member by the pull of the cable so that the cable will be rigidly gripped between the jaws of the clamp. Thus, the cable may be stressed, as may be desired, without danger of the slipping of the clamp while the cable will be securely anchored to extend above the trolley wire, and, as will now be appreciated, the anchor is equally applicable for use in a system employing either the clamps 13 or the clamps 14, or both.

Having thus described the invention, what I claim is:

1. In a wire anchor, a clamp including a body member having a fixed jaw, and a substantially U-shaped movable jaw having side

portions to straddle a wire confined between said side portions to lie between the jaws, the movable jaw being shiftable upon the body member in a plane at an angle to the plane of the fixed jaw for gripping a wire between the jaws.

2. In a wire anchor, a clamp including a body member having a fixed jaw, flanges on said member at opposite sides of said jaw and lying in a plane at an angle to the plane of the jaw, and a channel-shaped movable jaw shiftable upon the body member for gripping a wire between the jaws, said movable jaw being provided with side portions having flanges to coact with said first mentioned flanges and having the side portions thereof disposed to straddle the wire for confining the wire to lie between the jaws.

3. In a wire anchor, a clamp including a body member having side and end bars and provided with a fixed jaw extending between said end bars, flanges on the side bars, and a channel-shaped movable jaw shiftable upon the body member in a plane at an angle to the plane of the fixed jaw for clamping a wire between the jaws, the movable jaw having side portions provided with flanges to coact with said first mentioned flanges and having the side portions thereof disposed to straddle the wire for confining the wire to lie between the jaws.

4. In a wire anchor, a body member having side and end bars and provided at the rear ends of said side bars with eyes to accommodate anchoring elements, an inclined fixed jaw extending between said end bars, flanges on the side bars lying in a plane at an angle to the plane of the fixed jaw, and a channel-shaped movable jaw to embrace a wire and having flanges to coact with, said first mentioned flanges, the movable jaw being gradually increased in depth to substantially conform to the inclination of the fixed jaw and being shiftable upon the body member for clamping the wire between said jaws.

In testimony whereof I affix my signature.

ALBERT J. GURNEY. [L.S.]
